UNITED STATES PATENT OFFICE.

JOHN K. ROGERS, OF BROOKLINE, MASSACHUSETTS.

DESIGN FOR TYPE.

SPECIFICATION forming part of Design No. 13,098, dated July 25, 1882.

Application filed March 16, 1882. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing the font consist of an alphabet of sloped Roman capitals, with figures and points, with black shade on the right hand and lower margin, and a rayed diagonal

shade beyond the black one, as shown in the accompanying impression taken from the types themselves, and showing their exact form and outline.

I claim—

The design for types, as described and shown.

JOHN K. ROGERS.
